UNITED STATES PATENT OFFICE.

HARRIET LYONS REDMOND, OF BOSTON, MASSACHUSETTS, ASSIGNOR TO THE
WILLIAM CARTER COMPANY, OF NEEDHAM HEIGHTS, MASSACHUSETTS, A
CORPORATION OF MASSACHUSETTS.

UNDERRGARMENT.

1,414,203.

Specification of Letters Patent. Patented Apr. 25, 1922.

Application filed February 2, 1921. Serial No. 441,902.

To all whom it may concern:

Be it known that I, HARRIET LYONS REDMOND, a citizen of the United States, and a resident of Boston, in the county of Suffolk and State of Massachusetts, have invented an Improvement in Undergarments, of which the following description, in connection with the accompanying drawings, is a specification, like characters on the drawings representing like parts.

This invention relates to undergarments and particularly to a sanitary apron or like attachment thereto.

In order that the principle of the invention may be readily understood, I have disclosed a single embodiment thereof in the accompanying drawings, wherein—

Fig. 1 is a front elevation of a union suit adapted to have my invention applied thereto;

Fig. 2 is a rear elevation of the same garment; and

Fig. 3 is a detail in vertical section showing the preferred means for securing the sanitary apron to the garment.

The garment having my invention applied thereto or incorporated therein may be wholly knitted or wholly woven, with a knitted insert or inserts if desired. The garment having my invention applied thereto is a union undergarment which in the disclosed embodiment thereof has extending transversely across the back at about the waist line above the rear opening therein means for detachably securing to such undergarment a sanitary apron, said means being sufficiently low at the waist line so that said apron will not be displaced upwardly in bending the body while permitting stretching or yielding of the upper back portion of said undergarment, in combination with said apron, the latter having along its upper edge complementary securing means and being composed of waterproof material, whereby the inner waterproof face contacts directly with the nether portion of the union undergarment to which it is attached and the outer water proof face contacts directly with the outer garment, said apron extending to the knees and having a free lower edge and free lateral edges permitting it to hang straight in standing or walking and to conform without pull to the body in sitting, said apron being full at the lower end so as to cover the space between

the legs of the undergarment at the knees and to overlie the major portion of the legs of the undergarment from the waist to the knees and fully covering and protecting the rear opening of the undergarment.

Referring more particularly to the drawings, the garment is indicated generally at 1 as a union undergarment. I have here shown the union undergarment as having a woven upper part 1' to cover the upper 60 part of the body, and woven extremities 2, 2.

Desirably I provide one or more knitted inserts. In Fig. 1, I have shown a knitted insert 3 which may extend wholly about the body at the waist portion or only partly 65 thereabout. Herein the said knitted insert 3 extends wholly about the body, as is evident from a comparison of Figs. 1 and 2. Also vertically extending inserts 4, 4 are provided and may extend from the upper 70 edge of the garment down to the knitted insert 3, or to the bottom of the extremities 2 if desired. In the knitted insert 3 the wales of the knitted fabric desirably extend transversely of the garment, and the wales 75 of the knitted inserts 4 extend longitudinally 80 of the garment.

Thus, the garment is made very elastic, both transversely and longitudinally, even when made of woven material. The inserts 85 3, 4, or such inserts as may be provided, are secured by stitching to the edges of the woven sections or portions. A garment having a knitted insert or inserts is not herein broadly claimed, being claimed in a co- 90 pending application. The garment is here shown as having an open crotch portion 5, but this structure may be changed as required. The sanitary apron or member is indicated generally at 6, it being of any 95 suitable extent and desirably of some substantially waterproof material. While the said apron 6 may be permanently attached to the garment, it is desirably detachably secured thereto, and in such a way as to 100 permit of ready detachment therefrom. For this purpose I have herein represented the body garment as having a transversely extending tape 7, shown most clearly in Figs. 2 and 3. To said tape is secured desirably 105 means permitting the ready attachment and detachment of the apron. For this purpose, I have shown a series of fastening members 8 somewhat analogous to glove fasteners.

In this construction, each member 8 is 110

shown as socketed for the reception of projecting parts upon mating members 9 secured to the apron at its upper edge, but if desired this construction may be reversed. 5 Preferably, however, I provide the means 8 with the sockets, upon the body of the garment 1, since there is thus less liability of injury in laundering the garment.

The apron 6 is preferably provided with a 10 tape 10 transversely secured across its upper edge, said tape 10 having the mating, detachable, securing means 9 permanently secured thereto.

The apron 6 is adapted to be worn between the undergarment 1 and the outer clothing. So far as I am aware, I am the first to provide a union undergarment with an article of this character.

The insert 3 enables the wearer to have a 20 semi-fitted garment with buttons, which will pull over the hips and bust easily.

Having thus described one illustrative embodiment of my invention, I desire it to be understood that although specific terms are 25 employed, they are used in a generic and descriptive sense and not for purposes of limitation, the scope of the invention being set forth in the following claims.

Claims.

30 1. A union undergarment having therein a transversely extending, knitted insert at the back at substantially the waist line, the wales of said insert extending transversely, and a sanitary apron detachably secured to the exterior of said union undergarment just below said knitted insert, said apron being held in place by the self-positioning of the union undergarment.

2. A union undergarment having therein

a transversely extending knitted insert at 40 the back at substantially the waist line and a sanitary apron detachably secured to the exterior of said undergarment just below said knitted insert, said apron being held in place by the self-positioning of the union 45 undergarment.

3. A union undergarment having extending transversely across the back at about the waist line above the rear opening therein, means for detachably securing to such undergarment a sanitary apron, said means being sufficiently low at the waist line so that said apron will not be displaced upwardly in bending the body while permitting stretching or yielding of the upper, back 55 part of said undergarment, in combination with said apron, the latter having along its upper edge complementary securing means and being composed of waterproof material, whereby the inner waterproof face contacts 60 directly with the nether portion of the union undergarment to which it is attached and the outer waterproof face contacts directly with an outer garment, said apron extending to the knees and having a free lower 65 edge and free lateral edges permitting it to hang straight in standing or walking and to conform without pull to the body in sitting, said apron being full at the lower end so as to cover the space between the legs of the 70 undergarment at the knees and to overlie the major portion of the legs of the undergarment from the waist to the knees and fully covering and protecting the rear opening of the undergarment.

In testimony whereof, I have signed my name to this specification.

HARRIET LYONS REDMOND.
